[57] ABSTRACT

A drawing triangle having a pair of rollers in at least two of the sides, the rollers being mounted perpendicular to the edge of their respective sides. One set of rollers can be lifted from the paper either by having the sides slightly curved or having a pivot pin near the intersection of the sides having the rollers so that pressure applied on one side will cause the other side to lift.

FIG-6

ROLLER MOUNTED DRAWING TRIANGLE

The invention relates to a device for drawing, cutting, tracing, or similar purposes, having two sides which are perpendicular to one another and are interconnected at one end, each side being provided with two substantially cylindrical rolls which are spaced apart and project at least partly from the bottom face of the device.

Such a device, known as a drawing triangle, is disclosed in U.S. Pat. No. 2,752,685 of July 3, 1956 or Austrian Pat. No. 170,838. With the triangle of the prior art, each side carries a long axle provided with a cylindrical roll at each end thereof, with the rotary axis of each roll being parallel to the corresponding side of the triangle. Such a triangle as known in the art is designed for drawing a number of parallel lines as is required, for instance, when hatching a drawing.

In order to laterally displace one of the sides to a position which is parallel to itself, that side is subjected to a load in such a manner that the triangle will start to perform a tilting motion, causing the rolls of the other sides to be raised from the plane of the paper.

It is an object of the present invention to provide a device which which at least both sides which are perpendicular to one another each may be displaced lengthwise over a flat surface as a mobile ruler, the flat surface being the plane of the paper where a drawing triangle is concerned.

This object is achieved by the fact that the two rolls of each side are supported about two parallel axles which are perpendicular to the edge of the side upon which they are mounted. The triangle is provided with means which cause one side to rise or at least unload when one of the other sides is pressed against a flat surface.

In this manner, lines may be extended in a simple manner by pressing the relative side against the surface as with any conventional triangle.

Upon performing this entirely natural movement, the rolls of the inoperative side are raised from the surface, or at least are unloaded, so that they are prevented from interfering with the parallel guide of the side pressed downwardly.

Said raising or unloading of the inoperative rolls may be achieved by different provisions in the device, two of which are illustrated in the drawing, by way of example, for a drawing triangle.

In the drawing:

FIG. 1 is a top view showing a first embodiment of a drawing triangle according to this invention;

FIG. 2 shows a detailed side view along the arrows II—II in FIG. 1 at an enlarged scale, in unloaded condition;

FIG. 3 shows the same detailed side view as FIG. 2, but in a loaded condition;

FIG. 4 shows a top view of a drawing triangle according the a second embodiment of this invention;

FIG. 5 shows a detailed side view along the arrows V—V in FIG. 4 at an enlarged scale, in unloaded condition, and

FIG. 6 shows the same detailed elevational view as FIG. 5, but in a loaded condition.

The triangle according to FIGS. 1, 2 and 3 comprises mutually perpendicular sides 1 and 2 and hypotenuse 3. Usually such a drawing triangle is made of a relatively rigid, transparent plastic material.

Each side 1 and 2 is provided with two rectangular recesses 4, part of a cylindrical roll 5 extending through each said recess. Each roll 5 is rotatable about an axle 6, the ends of which are secured in bearings 7, which are provided on the upper surface of the triangle. The arrangement is such that the axles 6 are perpendicular to the length of the corresponding side. Each roll 5, which may be manufactured of plastic or metal, may also be provided with a stationary axle 6, the ends of which, in this instance, may be rotatably supported in the bearings 7. Each roll 5 is preferably provided with longitudinally extending grooves. Each roll 5 may be replaced by two disc-shaped wheels, spaced apart over a short distance on the same axle. In this instance the dual wheels will act as a cylindrical roll. Alternatively, each roll, farthest removed from the right angle, may be replaced by a disc-shaped wheel, provided the other rolls or dual wheels are retained.

The bearings 7 abut two opposed sides of the rectangular recess 4. Each roll 5 projects over a short distance from the underside of the triangle, in a conventional drawing triangle this projection being approximately in the order of 1 mm. Accordingly, the triangle rests with four rolls 5 on the plane of the paper, which is identified in FIGS. 2 and 3 by reference numeral 8.

It will be apparent that if the side 1, for instance, is moved lengthwise across the plane of the paper 8, the rolls of the side 2 will interfere with the movement, because they are only adapted to perform a rolling movement in one direction.

This problem is solved in the first embodiment by providing each side 1 and 2 with a predetermined fixed, upward curve in its middle, that is between the rollers, see FIG. 2. This curve may be fixed in various ways. One way is illustrated in the drawing, viz. with the aid of an a strip 9 having a concave underside. This strip is less deformable than the side to which it is secured and preferably consists of transparent plastic as well, so that the view of the plane of the paper under the triangle is hardly obstructed.

By glueing or welding such a strip 9 having a concave underside on the sides 1 and 2, both sides are slightly curved upwards between the rollers. It is understood that the strips 9 may form an integral part of the triangle, too.

The vertices of the triangle, in unloaded condition of the triangle, are thus nearer to the plane of the paper 8 than the parts of the sides between the rolls. The strips 9 substantially extend over the whole distance between the rolls.

The fixed curve may even be chosen so large that the triangle, in an unloaded condition, does not rest on the four rolls, but on the ends of the sides thereof.

When pressure is exerted from above on the strip 9 of the side 1 against the plane of the paper 8, the part of said side between the rolls will move towards the plane of the paper 8. Inasmuch as the rolls 5 are fixed pressure points, the right side 1, initially curved upwards, is straightened out, see FIG. 3. By having moved the ends of the side 1 in the upward direction, the whole side 2 is consequently raised, causing the rolls 5 of the side 2 to be raised from the plane of the paper, or at least to be unloaded to such an extent, that they will no longer interfere with the moving of the rolls 5 of the side 1.

Furthermore, it is possible to provide the sides 1 and 2 with a fixed curve without using an aid, such as the

strip 9. However, fatigue of the plastic material may cause the curve to become lost and as a consequence the proper functioning cannot be assured.

If the initial curve of the sides is omitted, satisfactory functioning is not achieved, because it is necessary that the rolls project from underneath the triangle only a slight distance, otherwise accurate drawing along the triangle would be out of the question. Consequently, the vertices are not raised enough if pressure is exerted between the rolls; also material fatigue is an additional unfavorable factor.

The triangle shown in the FIGS. 4, 5 and 6 substantially corresponds with the triangle shown in the FIGS. 1, 2 and 3, accordingly only the points of difference will be described hereinafter.

This embodiment appears particularly designated for side large triangles. The sides are not provided with an initial curve. The strips 9, if present, may therefore have straight undersides. With this embodiment use is made of a pin 10 which is secured to the underside of the triangle in the proximity of the inner side of the right angle. The projecting end of the pin 10 is slightly rounded, so that little friction occurs when the pin slides across the drawing paper. The length of the pin 10 is slightly greater than the distance which the rolls 5 project from the underside of the triangle. Thus, the flat triangle, in unloaded condition, is supported by the pin 10 and by the rolls 5 which are farthest removed from the pin 10.

If pressure is exerted on the strip 9 of the side 1, for instance, the roll 5 of the side 1 nearest to the pin 10 will move towards the plane of the paper 8. As the length of the pin 10 is greater than the projection of the roll, the side 2 is raised with the pressure point of the pin 10 on the plane 8 as a tilting point. Thus, the rolls 5 of the side 2 are raised from the drawing paper 8, or are at least unloaded and the triangle may be moved in the longitudinal direction of the side 1.

Accordingly, with the aid of the triangle of this invention, long lines may be drawn without utilizing a drawing machine. Hatching can be done by exerting pressure on the side not used for drawing.

The great advantage of this triangle is that it may be used without the draftsman having to perform any different movements from those he is accustomed to perform.

This triangle will be particularly useful in locations where there is no elaborate drawing machine with parallel guide available. Nevertheless, the draftsman has a complete drawing instrument at his disposal, which may be taken along wherever he goes.

It will be apparent that the invention is not limited to an isosceles triangle having two angles of 45°. A 30°-60° right triangle may also be constructed according to this invention. The hypotenuse may even be completely omitted so that the device only comprises two rulers in perpendicular relation to each other, these rulers being interconnected at one end.

The hypotenuse of the triangle may be provided with a set of rolls as well, although in practice there will be little need therefor.

Although this device has been described above for use in a drafting office, it will be apparent that it may also be used for cutting, tracing or marking out work-pieces in a machine shop. To this end, each side may be provided with a stylus or knife 12 (see FIG. 1) disposed in an approximately central position between the

rolls, this stylus or knife projecting from underneath the device a distance approximately equal to that of the rolls. If, in that instance, pressure is exerted on a side, the stylus or the knife will follow the downward movement.

If desired, the stylus or knife may be subjected to an additional amount of pressure by employing resilient means. With this a deeper cut may be achieved or a more uniform pressure if slight irregularities are met in the surface, to be cut or to be provided with lines.

By using a pen or pencil instead of a stylus, the resulting triangle may be used for making drawings. In that instance, upon moving the triangle a long pencilled or inked line will automatically be produced.

The foregoing description is given by way of example only and it should be understood that the scope of the invention is defined only by the following claims.

What is claimed is:

1. A marking guide comprising two arms which are perpendicular to one another and interconnected at one end, each of said arms being provided with two substantially cylindrical rolls which are spaced apart and project at least partly beneath the bottom surface of the guide, the two rolls of each arm being supported on two parallel axles, said axles being mounted substantially perpendicular to the edge of the arm upon which they are mounted, means to at least unload the rolls of one side when the other side is pressed toward a flat surface upon which the device is resting, said means being an upward curve of at least one arm, between the rollers of that arm.

2. The of claim 1 in which the curve is fixed by a strip 30 secured to an arm, said strip being less deformable than the arm to which it is secured and having substantially the same length as the distance between the two parallel rolls, said strip having a concave surface secured to the upper surface of an arm.

3. The guide of claim 2 in which a strip is fastened to each arm by glueing or welding.

4. The guide of claim 2 in which each strip forms an integral part of the device.

5. The guide of claim 1 in which on at least one arm, at a point between the rolls, a marking point extends from the underside of the device about the same distance as the rolls extend.

6. A marking guide comprising a right triangle, each of the arms adjacent the right angle having a pair of rollers, each roller mounted for rotation on an axle which is perpendicular to the edge of the arm, an opening under each roller so that the roller can project through the arm to contact a flat surface upon which the device may rest, each said arm having a slight upward curve at its center portion so that when that portion is pressed toward said flat surface the pair of rollers on the other arm will be lifted sufficiently to permit the pressed arm to be moved longitudinally.

7. A marking guide comprising two arms which are perpendicular to one another and interconnected at one end, each of said arms being provided with two substantially cylindrical rolls which are spaced apart and project at least partly beneath the bottom surface of the guide, the two rolls of each arm being supported on two parallel axles, said axles being mounted substantially perpendicular to the edge of the arm upon which they are mounted, means adapted to at least unload the rolls of one side when the other side is pressed toward a flat surface upon which the guide is resting, said means being a pin disposed in the proximity of the inner side of the right angle between the two arms, said pin projecting from underneath the device to a slightly greater extent than the rolls, and serving as a tilting point if one of the arms between the rolls is pressed downwardly.
